UNITED STATES PATENT OFFICE

137,613

DESIGN FOR AN ASH TRAY OR SIMILAR ARTICLE

Carl W. Gustkey, Wheeling, W. Va., assignor to Imperial Glass Corporation, Bellaire, Ohio, a corporation of Ohio

Application October 15, 1943, Serial No. 111,368

Term of patent 14 years

(Cl. D85—2)

To all whom it may concern:

Be it known that I, Carl W. Gustkey, a citizen of the United States of America and resident of Wheeling, county of Ohio, and State of West Virginia, have invented a new, original, and ornamental Design for an Ash Tray or Similar Article, of which the following is a specification, reference being had to the accompanying drawing, forming part thereof, in which—

Figure 1 is a perspective view of an ash tray showing my new design; and

Figure 2 is a perspective view of the same as viewed from a point substantially diametrically opposite from that depicted in Figure 1.

I claim:

The ornamental design for an ash tray or similar article, substantially as shown.

CARL W. GUSTKEY.
